D. W. COREY.

THREAD CONTROLLING MECHANISM FOR SEWING MACHINES.
APPLICATION FILED JUNE 3, 1904.

1,075,695.

Patented Oct. 14, 1913.

UNITED STATES PATENT OFFICE.

DANIEL W. COREY, OF ST. LOUIS, MISSOURI, ASSIGNOR TO UNION SPECIAL SEWING MACHINE COMPANY, OF CHICAGO, ILLINOIS, A CORPORATION OF ILLINOIS.

THREAD-CONTROLLING MECHANISM FOR SEWING-MACHINES.

1,075,695.

Specification of Letters Patent. Patented Oct. 14, 1913.

Application filed June 3, 1904. Serial No. 211,030.

To all whom it may concern:

Be it known that I, DANIEL W. COREY, a citizen of the United States, residing at St. Louis, in the State of Missouri, have invented certain new and useful Improvements in Thread-Controlling Mechanism for Sewing-Machines, of which the following is a description, reference being had to the accompanying drawing and to the letters and figures of reference marked thereon.

My invention relates to an improvement in sewing machines, and particularly to an improvement upon the Union Special zig-zag and straight-away-stitch machine, which is illustrated in the patent of R. G. Woodward No. 890,582, granted June 9, 1908. The machine above referred to is used principally in connection with the closing of the uppers of shoes at the rear portion, the object being to first sew the two superposed edges of the upper together a short distance by a line of straight-away sewing, and then by a line of zig-zag sewing so that, when the pieces of leather are spread out flat, there will be no ridge upon the inside of the shoe, except at the very top of the rear part.

In practice, it has been found that when stitching the lighter grades of leather, such as in the manufacture of fine shoes, with the ordinary tension devices adjusted for straightaway stitching, when the zig-zag stitch was being sewed, the seam would be too tight, so that on such light goods, the stock is liable to be pulled together forming a ridge, there not being enough thread given up to allow the overstitched seam to lie flat.

The object of the present invention is, therefore, to provide means for loosening up the tension on the thread when the machine operates to make the zig-zag stitches.

In carrying out the invention mechanism is provided whereby the tension on the thread may be varied when passing from the straightaway stitching to the zig-zag stitching. As a further means of aiding in accomplishing this result, I provide the presser foot with a tongue across which the needle lays its thread when forming the zig-zag stitches.

The invention consists in the matters hereinafter described and referred to in the appended claims.

The invention is illustrated in the drawings, in which,

Figure 1 represents a front elevation of so much of the sewing machine, as is necessary to a complete understanding of the invention, Fig. 2 is a perspective of the presser foot and a portion of the throat plate coöperating therewith, Fig. 3 is a top plan view of the presser foot, and Fig. 4 represents the style of stitching accomplished on this machine.

In these drawings, A represents the bed plate of the machine, B the goose neck, C the needle lever, N' the needle bar, a the needle, and D the needle gate in which the needle bar reciprocates. The needle gate is connected to the depending arm 1, of the rock shaft 2, which is oscillated by the segment 3 operated by an eccentric carried by the gear wheel 4. The oscillation of the needle gate causes the needle to deposit the zig-zag stitches. By means of the rod 5, which is under the control of the operator, the connection between the segment 3 and the rock shaft 2 is controlled so that the needle gate is either vibrated or remains at rest, thus depositing either the zig-zag or straight-away stitching. All of these parts are disclosed in detail in the patents granted to R. G. Woodward, February 23, 1904, No. 753,187, and June 9th, 1908, No. 890,582, and will not need further description at this time as they form no part of my invention. In the usual operation of this machine it has been found that the tension when adjusted properly for straightaway stitching is too tight for zig-zag stitching, thus causing in light goods a rib where the goods should lie flat. I have, therefore, provided two tensions, Q, which is the ordinary tension, and P an auxiliary tension.

An arm L is connected with the lever pivoted in the bracket C' and operated by the rod 5 to control the position of the needle. This arm L has adjustably connected at its upper end a fork K provided with wedge shaped ends N which enter between the disks of the auxiliary tension P when the arm is raised, thus releasing the auxiliary tension from the thread. This releasing of the auxiliary tension takes place when the connection between the rock shaft 2 and the segment 3 is controlled, so as to cause the needle to vibrate to deposit the zig-zag

- stitches. It will be noted that when the operator moves the controller so as to change the character of the seam from zig-zag stitching to straight-away stitching the auxiliary tension will be automatically released or applied to the needle thread. When sewing on heavy material and it is desired to maintain a constant tension on the needle thread whether making straightaway or zig-zag stitching the screw which connects the fork K to the arm L is loosened and the fork adjusted downward until it is in a position where it will not engage the tension disks in either position of the arm L.
- 15 As a further means for controlling the thread when making the zig-zag stitches, I have provided the presser foot S with a tongue T which lies in the path of vibration of the needle so that the said needle lays its 20 thread over said tongue. As the goods are fed forward the stitches slip off from the tongue. This tongue serves to form slack in the thread and retain the same so that stitches will not be skipped as might occur 25 with a loose tension. A similar tongue T', see Fig. 2, is provided on the throat plate over which the looper thread is drawn.
- By the above described devices, I can produce a straightaway stitched seam having 30 proper tension on the threads to make a tight stitch and also a zig-zag stitched seam with a sufficiently loose tension on the threads so that the same may be opened out flat.
- 35 Having thus described my invention, what I claim as new and desire to secure by Letters Patent is:—
1. In a sewing machine, the combination of a work support, a presser foot and stitch-forming mechanism, including a needle, means for vibrating said needle laterally to 40 form cross stitching, means for suspending the lateral vibrations of said needle, whereby a line of stitching may be produced which 45 is substantially in line with one of the rows of needle punctures in the cross stitching, and a slack thread-forming finger located entirely at one side of the path of the needle, when forming the straight line of stitching

and between the extreme lateral positions of the needle when making the cross stitching, whereby the cross threads are laid over said thread finger.

2. In a sewing machine, the combination of a work support, a presser foot, a slack 55 thread forming finger, stitch forming mechanism including a needle, means for vibrating said needle, whereby a stitch is formed first on one side and then the other of said finger and zig-zag stitches produced, means for suspending the vibrations of said needle whereby the needle forms stitches on one side of said finger and straightaway stitching produced, a tension device, and means operating in connection with said tension device 60 for decreasing the tension on the needle thread when forming the stitches on first one side and then the other of said finger.

3. In a sewing machine, the combination of a work support, a presser foot, a slack 70 thread forming finger, stitch forming mechanism, including a needle, means for vibrating said needle whereby zigzag stitches are formed across said thread finger, means for suspending the vibrations of said needle, 75 whereby a straight line of stitching is formed at one side of said stitch finger; a constant tension device and an auxiliary tension device, means operated by the means for causing the vibration of the needle for 80 releasing the auxiliary tension when producing zigzag stitching.

4. In a sewing machine, the combination of stitch forming mechanism including a needle, means for vibrating the same laterally, devices for controlling the lateral movement of the needle, a tension device comprising tension disks, means for decreasing the tension including an arm, a fork adjustably carried thereby and adapted to enter between the disks of the tension, substantially 90 as described.

In testimony whereof I affix my signature, in presence of two witnesses.

DANIEL W. COREY.
